United States Patent Office

Des. 182,740
Patented May 6, 1958

182,740

CHAIR OR SIMILAR ARTICLE

Lawrence I. Peabody, Rindge, N. H., assignor to Kroehler
Mfg. Co., Naperville, Ill., a corporation of Illinois

Application October 21, 1957, Serial No. 48,171

Term of patent 7 years

(Cl. D15—1)

Fig. 1 is a front perspective view of a chair or similar article, showing my new design; and

Fig. 2 is a rear perspective view thereof.

The side of my chair or similar article opposite that shown is symmetrically reverse but otherwise identical.

I claim:

The ornamental design for a chair or similar article, as shown and described.
